ALBERT J. LINDEMANN AND WALTER C. LINDEMANN, OF MILWAUKEE, WISCONSIN,
ASSIGNORS TO A. J. LINDEMANN & HOVERSON COMPANY, OF MILWAUKEE, WIS-
CONSIN, A CORPORATION OF WISCONSIN.

HYDROCARBON-BURNER.

1,339,207.

Specification of Letters Patent.

Patented May 4, 1920.

Application filed July 18, 1919. Serial No. 311,777.

To all whom it may concern:

Be it known that we, ALBERT J. LINDEMANN and WALTER C. LINDEMANN, citizens of the United States, and residents of the 5 city of Milwaukee, in the county of Milwaukee, State of Wisconsin, have invented certain new and useful Improvements in Hydrocarbon-Burners, of which the following is a specification.

10 The improvements relate to burners of the "wickless" variety, in which an annular trough is provided, and a wick of asbestos or other non-combustible material placed therein. In such devices it is desirable to 15 obtain a quick and even distribution of the liquid hydrocarbon fuel around the bottom of the wick, and, when the burner is constructed and arranged to be drained, a quick draining of the oil therefrom. Among the 20 objects of the present improvements are the production of a burner trough having these characteristics, of simple construction and effective operation, and to so construct the trough that it can be manufactured at a 25 minimum of labor and materials.

The improvements are illustrated in the accompanying drawings, referred to herein, in which Figure 1 is a plan of a burner trough embodying the improvements; Fig. 2 30 a vertical section of the same on the line 2-2 of Fig. 1, looking in the direction indicated by the arrows, and Fig. 3 a similar section of a fragment of the trough on the line 3-3 of Fig. 1, looking in the direction indicated by 35 the arrows.

The burner trough A is composed of a single piece of sheet metal drawn or otherwise formed into a trough A, with flanges G and H around its upper edges for the reception of a combustion chamber, and a 40 flammable diaphragm F extending across the central space.

This trough is so formed that its bottom is inclined toward the fuel supply pipe B 45 from a point diametrically opposite said pipe, and at its shallowest point it is provided with a small bottom indentation E, which supports the wick C above said bottom at that point. On both sides of the 50 trough near the bottom are lateral indentations D on a level with the upward bottom indentation E, one of these indentations being provided on each side of the trough so that they extend toward the middle of the

trough from its sides and form a shelf or 55 support for the wick, leaving only a narrow passage between them. It will be seen therefore that the wick is supported horizontally above the bottom of the trough while the 60 bottom of the trough inclines downwardly toward the inlet and outlet opening A' leading to the fuel supply pipe. In this manner a free channel for the influx and distribution and the outflow of the liquid fuel is provided around the bottom of the wick, 65 and the wick is supported in such a manner that its upper and lower edges will be horizontal and will absorb the liquid fuel and carry it up and present it for vaporization evenly throughout its entire circumference. 70 It will also be seen that the trough is made of a single piece of material without additional parts, and that the wick supporting devices are formed by the simple method of producing indentations in its sides and 75 bottom.

In operation fuel is admitted through the supply pipe B in sufficient volume and runs around beneath the wick, reaching the part of the wick farthest from the supply pipe 80 as quickly as the part immediately above said pipe, and presenting itself for absorption simultaneously at all points. When the burner is drained the level of the liquid fuel falls instantly throughout the entire trough 85 and the flame is thereby reduced at substantially the same rate throughout. The draining of the trough is also quick and complete, and any particles of carbon or other matter that may have found their way 90 to the bottom of the trough are carried off with the liquid and do not clog or obstruct the trough in any way.

What we claim is:

1. An annular trough comprising in its 95 construction a trough proper, composed of sides and bottom, and having an inlet and outlet opening in said bottom, said bottom being inclined upwardly from said opening to a point distant therefrom, a portion of 100 said bottom being elevated at said point, and the bottom inclining downwardly therefrom on both sides to said opening.

2. An annular trough comprising in its 105 construction a trough proper, composed of sides and bottom, and having an inlet and outlet opening in said bottom, said bottom being inclined upwardly from said opening

to a point distant therefrom, a portion of said bottom being elevated at said point, and the bottom inclining downwardly therefrom on both sides to said opening, in combination with a wick device having its bottom resting on said upwardly extending portion of the bottom and supported horizontally in said trough.

3. An annular trough comprising in its construction a trough proper, composed of sides and bottom, and having an inlet and outlet opening in said bottom, said bottom being inclined upwardly from said opening to a point distant therefrom, a portion 10 of said bottom being elevated at said point, and the bottom inclining downwardly therefrom on both sides to said opening, in combination with a wick device having its bottom resting on said upwardly extending 15 portion of the bottom and supported horizontally in said trough, said wick being out of contact with the said bottom at other points.

4. An annular trough comprising in its construction a trough proper, composed of sides and bottom, and having an inlet and outlet opening in said bottom, said bottom being inclined upwardly from said opening and on both sides thereof to a point distant therefrom, in combination with a wick device having its lower part at the said point of the bottom and supported horizontally in said trough, said wick being out of contact with said bottom at all other 35 points.

5. An annular trough comprising in its construction a trough proper, composed of sides and bottom, and having an inlet and outlet opening in said bottom, said bottom being inclined upwardly from said opening to a point distant therefrom, a portion of said bottom being elevated at said point, and the bottom inclining downwardly therefrom on both sides to said opening, and said 40 trough also having inward lateral projections between said opening and said upwardly projecting portion of the bottom, said lateral projections being above the bottom.

6. An annular trough comprising in its construction a trough proper, composed of sides and bottom, and having an inlet and outlet opening in said bottom, said bottom being inclined upwardly from said opening 55 to a point distant therefrom, a portion of said bottom being elevated at said point, and the bottom inclining downwardly therefrom on both sides to said opening, and said trough also having inward lateral projections between said opening and said upwardly projecting portion of the bottom, said lateral projections being on a level with the upper part of the said upwardly projecting portion of the bottom.

7. An annular trough comprising in its

construction a trough proper, composed of sides and bottom, and having an inlet and outlet opening in said bottom, said bottom being inclined upwardly from said opening to a point distant therefrom, a portion of 70 said bottom being elevated at said point, and the bottom inclining downwardly therefrom on both sides to said opening, and said trough also having inward lateral projections between said opening and said upwardly projecting portion of the bottom, said lateral projections being above the bottom, in combination with a wick device supported horizontally on said upwardly projecting portion of the bottom and said inward lateral projections.

8. A trough comprising in its construction a trough proper, having an outlet and inlet opening, and a bottom inclined upwardly from said opening, in combination with a 85 wick device supported above said bottom throughout to leave a space for the free passage of fluid between its lower edge and the said bottom.

9. A hydrocarbon burner device comprising in its construction an annular trough, composed of a single piece of sheet metal and having an inlet and outlet opening at the bottom thereof, wick supporting devices formed by indenting the sides and bottom 90 of the metal forming the trough at different points throughout its circumference.

10. A hydrocarbon burner device comprising in its construction an annular trough, composed of a single piece of sheet 100 metal and having an inlet and outlet opening at the bottom thereof, wick supporting devices formed by indenting the sides and bottom of the metal forming the trough at different points throughout its circumference, and flanges at the upper edges of said trough extending outwardly and upwardly 105 therefrom, formed of the same piece of sheet metal as the trough.

11. The combination of an annular trough, 110 said trough having an inlet and outlet opening in its bottom, a wick device substantially filling said trough from side to side and from the top to a point near the bottom thereof, and means for supporting the said wick in horizontal position above the bottom of the trough.

12. The combination of an annular trough, 115 said trough having an inlet and outlet opening in its bottom, a wick device substantially filling said trough from side to side and from the top to a point near the bottom thereof, and means for supporting the said wick in horizontal position above the bottom of the trough, the bottom of said 120 trough being inclined upwardly from the opening and on both sides thereof to a point distant from said opening.

13. The combination of an annular trough, 125 said trough having an inlet and outlet open-

ing in its bottom, a wick device substantially filling said trough from side to side and from the top to a point near the bottom thereof, and means for supporting the said 5 wick in horizontal position above the bottom of the trough, comprising indentations in the sides of the trough projecting inwardly thereinto and reducing the diameter of the trough at that point so that it is less 10 than the diameter of the wick device.

14. The combination of an annular trough, said trough having an inlet and outlet opening in its bottom, a wick device substantially filling said trough from side to side 15 and from the top to a point near the bottom thereof, and means for supporting the said wick in horizontal position above the bottom of the trough, comprising inward 20 projections in the sides of the trough which reduce the diameter thereof to less than the diameter of the wick device.

15. The combination of an annular trough, said trough having an inlet and outlet opening in its bottom, a wick device substantially 25 filling said trough from side to side.

and from the top to a point near the bottom thereof, and means for supporting the said wick in horizontal position above the bottom of the trough, comprising an upward projection in the bottom of the trough 30 upon which the wick device is supported located at a point distant from the opening.

16. The combination of an annular trough, said trough having an inlet and outlet opening in its bottom, a wick device substantially 35 filling said trough from side to side and from the top to a point near the bottom thereof, and means for supporting the said wick in horizontal position above the bottom of the trough, comprising an upward projection in the bottom of the trough 40 upon which the wick device is supported located at a point distant from the opening, and other projections between said upward projection and the opening. 45

Witness our hands this 15th day of July, 1919, at the city of Milwaukee, in the county of Milwaukee, State of Wisconsin.

ALBERT J. LINDEMANN.
WALTER C. LINDEMANN.
